UNITED STATES PATENT OFFICE.

GEORGE D. GOODRICH AND HORACE A. GOODRICH, OF JOLIET, ILLINOIS.

IMPROVEMENT IN CLAY-PIPE DIES.

Specification forming part of Letters Patent No. **58,851**, dated October 16, 1866.

To all whom it may concern:

Be it known that we, G. D. GOODRICH and H. A. GOODRICH, of the town of Joliet, in the county of Will and State of Illinois, have invented new and useful Improvements in the Dies of the Machines Working and Manufacturing Clay or any other suitable Material into Pipes; and we do hereby declare that the following is a full and exact description thereof, reference being had to the accompanying drawings, making part of this specification, in which—

Figure 1 represents a vertical section of the die, and Fig. 2 the front view of the same.

The nature of our invention consists in the die, the core of which is detached from the feeding-shaft of the clay-pipe machine, and is placed on its own stationary shaft in such a manner as to revolve with and by the motion of the clay, as this comes from the tempering-mill, thereby preventing injury and breaking of the pipe, as would be the case with the machines having stationary cores.

It consists, also, in an improved face-plate of the die, the funnel-shaped portion of which enters the tempering-mill, and its interior surface making a perfect inclined plane with the tapering interior surface of the mill.

To enable others skilled in the art to make and use our invention, we will describe its construction and operation.

In our improved die the core consists of a cone, Fig. 1, cut at a point, *a*, transversely and parallelly to its base, in two parts, the upper part, *A*, of which, being solid, is firmly set on the immovable bar or bridge *B*, and having a shaft, *C*, protruding downward, while the lower portion, *D*, of the cone, which may be called "core proper," is hollow, and by means of its hub *E* is set on the shaft *C*, and is permitted to revolve on it.

With these arrangements the core, being capable of revolving with and by the motion of the clay as it approaches and passes the orifice of the die under the pressure of the tempering-mill, prevents injury and breaking of the pipe, which would occur should the core be stationary, while at the same time the

bridge *B* retards the revolution of the clay; and hence the revolution of the pipe, as it comes out of the die—a matter of importance in the manufacture of pipes, and an operation which is not performed in a machine in which the core is connected with or forms a part of the feeding-shaft; besides that, the conical shape of the core lessens its resistance to the clay.

The face-plate *F* of our die has a funnel-shaped ring, *G*, cast upon and forming part of the same, which, when the face-plate is put on, enters the mill and makes, with another detached and stationary funnel, *H*, a perfect inclined plane. Said funnel *H*, making a separate part of the face-plate, has its interior surface shaped in such a manner as to form a perfect continuity with the inclined plane of the interior surface of the mill when put inside.

For different sizes of the pipes different face-plates have to be used, but in each of them the funnel-shaped ring *G* is so constructed that its interior surface makes, in every case, one continuous inclined plane with the surface of the funnel *H*.

The advantages of this face-plate consist in its lightness, adaptation for pipes of various sizes, and exemption from the pressure of clay upon it; and hence an exemption from that tendency, which the pressure of the clay always shows, to displace the funnel out of its true position.

The above description of the parts of our dies shows conclusively that, its core being disconnected from the working-shaft preserves always its center in proper and true position, while in other machines the position of the center of the core, depending from the position of the shaft, is liable to be changed by the pressure of the clay or some other causes.

Having thus described our invention, we state that we do not claim the invention of a conical core or a stationary bridge, nor a loose or revolving core on a revolving shaft; but

What we do claim, and desire to secure by Letters Patent, is—

The improvement in the machines, of any construction, used for the manufacture of pipes by which a rotary or spiral motion is given to the clay or other suitable material in the process of manufacture, consisting in the die with its revolving core detached from the feeding-shaft and placed upon a stationary shaft, and its funnel-shaped face-plate, con-

structed and operating substantially as herein described and specified.

GEORGE D. GOODRICH.
HORACE A. GOODRICH.
